UNITED STATES PATENT OFFICE.

HARVEY H. TROXEL, OF ASHLAND, OHIO.

WASHING-MACHINE.

1,399,451.

Specification of Letters Patent.

Patented Dec. 6, 1921.

Application filed January 7, 1921. Serial No. 435,583.

To all whom it may concern:

Be it known that I, HARVEY H. TROXEL, a citizen of the United States, residing at Ashland, in the county of Ashland and State 5 of Ohio, have invented certain new and useful Improvements in Washing-Machines, of which the following is a specification.

My invention relates to improvements in washing machines, and more particularly 10 to that class or type of power washers in which a rotary cylinder is employed.

In this class or type of machines there is a great tendency of the clothes when in the rotary washer cylinder to assume a ropy 15 knotted condition, this tendency being particularly manifest where the cylinder is rotated in one direction only (commonly known as a "one-way" cylinder), and the primary object of my invention is, therefore, 20 to eliminate this tendency in such washer cylinders and at the same time improve the washing or cleansing properties thereof.

A further object is the provision of a generally 25 improved clothes separating and intercepting element which may be readily inserted in or removed from rotary washer cylinders of the general classes indicated, and when inserted will divide and maintain the clothes within the cylinder in batches and not only entirely eliminate any tendency of the clothes to assume a ropy or knotted condition but improve the washing or cleansing properties of the cylinder.

With the above mentioned and other ends 35 in view, the invention consists in the novel construction, arrangement and combination of parts, hereinafter described, illustrated in one of its embodiments in the accompanying drawings and particularly pointed out in the appended claims.

Referring to the drawings, forming a part of this specification, Figure 1 is a view of an ordinary rotary washer cylinder detached 45 and equipped with my improved clothes intercepting and separating element or device, the door being removed.

Fig. 2, a similar view of the same, a portion 50 of the side walls of the cylinder being removed to show the central portion of the clothes intercepting and separating element.

Fig. 3, a sectional view of the same taken on line 3—3 of Fig. 2, the improved washer being equipped with two batches of clothes

to illustrate the relative arrangement and co-action of the parts.

Fig. 4, an enlarged fragmentary view of the improved intercepting and separating element detached, and illustrating in particular the interposed pervious flexible material or fabric carried by the frame portion thereof.

Fig. 5, an edge view of the clothes intercepting and separating element detached, and illustrating in particular the relatively flat central clothes intercepting fabric portion as suspended horizontally from the frame.

Similar numerals of reference designate like parts throughout all the figures of the drawings.

The rotary washer cylinder 1, may be of any suitable and convenient form, and so likewise as to the general interior arrangement and manner of driving or operating the same.

For the purpose of illustration only, I have shown my improved device mounted in a cylinder having concavo-convex shaped heads 1^a, and provided with axial stub shafts or trunnions 1^b.

As a convenient means of removably inserting and securing the improved clothes intercepting and separating element within the cylinder and between the heads 1^a, the improved device is preferably provided with a frame 2, corresponding in outline and general dimensions to the general form and outline of the largest interior dimensions of the cylinder. The frame 2, therefore, comprises the transversely extending members 2, and the curved end members 2^a, the latter being preferably of resilient or spring material so that the end members 2^a, may be contracted somewhat in forcing the frame 95 into the cylinder and between the heads 1^a, by inserting the same through the door portion 1^c, or clothes receiving opening normally closed by the segmental lid or cover 1^b.

The supporting frame is provided with suitable foraminous or pervious material, preferably loosely mounted within the frame as shown most clearly in Figs. 3 and 5 of the drawings. The clothes intercepting and separating material or fabric is preferably loosely and flexibly mounted within the frame, and may be formed of any suitable and convenient material having the func-

tions mentioned, such material in the present instance, comprising cross chain members 2^b, having their intersecting portions connected to each other and connected at their 5 ends by means of hook members 2^c, extending through openings 2^d, in the frame. The frame 2 is preferably formed of a single length of wire or round bar material and united or welded at its ends to form a continuous piece.

In order to permit the separated batches of clothes 3, to move toward and from each other and toward and from the center of the cylinder, as illustrated, for example in Fig. 15 3 of the drawings, the pervious or foraminous material such as the chain members 2^b, is preferably so arranged and connected that when the frame is moved to a horizontal position substantially as shown in Fig. 20 5 of the drawings, the chain members will form a relatively flat central clothes intercepting body portion *a*, with inclined marginal portions *b*, and it will be obvious that the pervious material *a* and *b*, will not only 25 separate the batches 3 of the clothes, but will move to and fro with the latter as the cylinder is rotated, thus not only preventing the entangling or knotting of the clothes but improving the action of the parts in 30 cleansing the clothes.

Having thus described one of the embodiments of my invention, without having attempted to set forth all the forms in which it may be made, or all the modes of its use, 35 what I claim and desire to secure by Letters Patent, is,—

1. In a washer, a rotary washer cylinder

provided with a transversely extending axially located pervious flexible partition adapted to separate the clothes into batches 40 and to move to and fro with the latter during the rotation of the cylinder.

2. In a rotary cylinder washer, a clothes separating partition comprising a flexible supporting frame corresponding in form to 45 the internal dimensions of the cylinder, and a relative movable fabric body comprising a relatively flat central clothes intercepting body portion and inclined marginal portions.

3. In a washing machine, the combination 50 with the rotary washer cylinder, of a frame removably mounted therein transversely of the direction of rotation, and clothes intercepting and separating foraminous material loosely carried by said frame 55 and adapted to swing from one side to the other with the separated clothes as the cylinder is rotated.

4. In a washing machine, including a rotary washer cylinder including bilged 60 heads, a resilient contractible frame corresponding in form and dimensions to the largest internal dimensions of said cylinder and heads and insertible from the perimeter of said cylinder, and clothes separating 65 pervious material flexibly carried within said frame and separating said cylinder into clothes washing compartments, said pervious material swinging to and fro as the cylinder is rotated.

In testimony whereof I have affixed my signature.

HARVEY H. TROXEL.
